UNITED STATES PATENT OFFICE.

WILLIAM H. SCHNEIDER, OF MILWAUKEE, WISCONSIN, ASSIGNOR TO ARTHUR C. KOOTZ, OF MILWAUKEE, WISCONSIN.

TINSEL AND THE LIKE AND METHOD FOR THE MANUFACTURE THEREOF.

Application filed January 10, 1925. Serial No. 1,710.

This invention relates to improvements in tinsel and the like and methods for the manufacture thereof.

It is the primary object of this invention 5 to provide and produce novel and improved articles adapted for novel uses both decorative and practical and to effect economies whereby the novel and improved articles embodying this invention may be made at considerably lower cost than such articles as 10 have heretofore been used for corresponding purposes.

More specifically stated it is the object of 15 this invention to produce a tinsel-like article in which the laterally and radially projecting strips or wire-like members are integrally joined to each other so that no precautions need be taken against the loss of such strips from the central core, which 20 usually comprises a twisted strand of string or wire.

It has been a general practice merely to 25 twist short lengths of wire into the strands of two flexible core members comprising strings or the like. The positioning of the 30 transverse strips or wires in these strands has usually depended solely upon friction. As a result the tinsel so made deteriorates rapidly and does not long remain ornamental because of the loss of the individual 35 strips or wires dependent upon friction for their positioning. It has been proposed to secure such strips or wires in place through the employment of some substance rendering 40 such strips or wires adherent to the core and to each other. This, however, entails an extra operation increasing to some extent the cost of manufacture. The present invention contemplates a construction in which 45 the core and the transverse strips may all be integral, each with the other, and no twisted strands are necessary except in so far as the core may require re-enforcement or in so far as the use of strips upon either side 50 thereof may facilitate the twisting of that portion of the core which is integral with the strips as aforesaid. Thereby a permanently enduring tinsel may be constructed at low expense. The articles produced in accordance with this invention are useful for other purposes besides their utility as Christmas trees. I have found, for example, that devices embodying this invention may be successfully employed in the 55 manufacture of artificial Christmas trees

and are admirably suited for use as aerials for the reception of radio signaling. It is therefore an object of this invention to produce articles which will be suitable for the additional purposes above enumerated. 60

It is a further object of this invention to provide for the application of color designs to tinsel. So far as I am aware colors heretofore applied to tinsel and the like have been applied by spraying or dipping and it 65 has been impossible to produce any preconceived pattern on the tinsel. It is one of the purposes of the present invention to provide for the production of patterns of any desired character upon the tinsel. 70

In the drawings:

Figure 1 is a diagrammatic plan view illustrating various stages in a method by which this invention may be practiced.

Figure 2 is a section taken on line 2—2 of 75 Figure 1.

Figure 3 is an enlarged detail taken on the section indicated at 3—3 of Figure 2.

Figure 4 is an enlarged detail showing modifications of certain of the parts appearing in Figure 2. 80

Figure 5 illustrates a further modification.

Figure 6 is an enlarged detail in side elevation of a fragment of tinsel or the like 85 embodying this invention.

Figure 7 is a diagrammatic side elevation of a fragment of tinsel in various stages of manufacture illustrating the application of color in pattern to one side of the strip from 90 which the tinsel is made whereby the pattern will appear on the finished tinsel.

Figure 8 is a detail view showing how my improved tinsel may be formed into a representation of the branch of an evergreen 95 tree.

Figure 9 is a fragmentary vertical axial section through an artificial tree incorporating the devices shown in Figure 8.

Figure 10 is a side elevation of a loop 100 aerial embodying this invention.

Figure 11 is a detail view of a fragment of a preferred aerial construction showing the same in various stages of manufacture.

Like parts are identified by like reference 105 characters throughout the several views.

It will be understood that the machine illustrated diagrammatically in Figure 1 comprises no part of the subject matter of the present application and is merely illustrated 110

to indicate the method by which articles embodying this invention may be manufactured. Upon a bed 15 of the machine are mounted journal boxes 16 which support the trunnions 17 on the roll 20 of ribbon from which the tinsel is constructed in accordance with this invention. The ribbon comprising roll 20 may be made of paper, cloth, or metallic foil, or any other flexible and light-weight substance of the requisite tensile strength. Preferably aluminum foil or copper foil is used as the material for the ribbon comprising roll 20. If the tinsel is to be used for the purpose of ornamenting a Christmas tree the material of roll 20 will preferably comprise aluminum foil. If, however, electrical conductivity is desirable copper foil will preferably be used. Metallic foil has certain advantages over paper and the like in that it tends to retain its shape, being highly flexible without being unduly resilient.

After the ribbon 25 leaves roll 20 it passes beneath a transfer roll 26 having peripheral ribs 27 and 28. The rolls 29 are in contact with ribs 27 and 28 and transmit thereto coloring pigment or dyes such as inks or the like. The ribs 27 thereupon transmit the inks or paints to the web or ribbon 25 upon which a design is imprinted according to the form of ribs 27 which, for the sake of simplicity, are represented merely as printing straight lines of color 30.

The colored web is now fed across an anvil or stationary shear blade 32 which is apertured at 33. A vertical reciprocable knife or movable shear blade 35 is supported for movement to and from shear blade 32. The operative cutting edges 36 of the knife 35 are disposed at an obtuse angle with reference to each other and the movement of the knife is such that as it descends it will cut into the margins of web 25 toward the center thereof to produce simultaneously cuts in each margin. The portion of the knife at the apex 37 of cutting margins 36 does not contact with the web 25 so that a central uncut portion 38 remains after the knives have moved to their extreme downward position. As indicated in Figure 2 the knife 35 may conveniently be actuated from a worm 39 through the worm gear 40, shaft 41, bevel gears 42, shaft 43, crank 44, and connecting rod 45.

The movable knife 35 is provided with an aperture 46 corresponding to the aperture 33 of the lower shear blade 32. Cords or wires such as may comprise flexible tension members suitable for the purpose for which the completed article is intended are shown at 50 and 51 and pass respectively through apertures 46 and 33 whereby they are positioned above and below the central uncut portion of web 25.

A movable carriage 55 is guided for movement with reference to the bed 15 of the machine and carries a rotor 56 to which the ends of the flexible tension members 50 and 51 are attached. The rotor 56 may conveniently be driven by a pinion 57 providing power through a worm shaft 58, and worm gear 59 from the screw 39. The carriage will be moved in any suitable manner along the bed of the machine in accordance with the rapidity with which the web may be fed between the shear blades 35 and 32. As the carriage moves the rotor 56 is in operation to twist the flexible tension members 50 and 51 which, due to their proximity upon either side of the uncut central portion 38 of the web will result in twisting such portion whereby the transverse elements designated generally at 60 and produced by the multiplicity of lateral cuts in the web are turned to project at various radial angles from the central core comprising the imperforated strip 38 as re-enforced by the tension members 50 and 51.

Where foil is used, it is well for practical purposes to employ the tension members 50 and 51. The method may be practiced, however, without such members where the material of which the tinsel is constructed has adequate tensile strength it is only necessary to fasten the end of the uncut portion 38 of such material to the rotor 56 or otherwise to twist the material to the desired extent. It should be understood that members 50 and 51 serve only as re-enforcing means and as a convenient means for applying twisting or torsional pressure to extremely light-weight material such as foil or the like, particularly where such material has low tensile strength.

For the purposes of illustration the web is illustrated in Figure 1 as issuing from the shears 37 and 32 in the plane ribbon. As a matter of fact, however, with the rotor 57 in operation the torsional effect thereof will be transmitted through the ribbon as far as the shears themselves work. Any further torsional effect is arrested due to the fact that the flexible tension members 50 and 51 are there guided through apertures 46 and 33.

After the torsional effect upon the slitted web has continued for a short space of time the laterally projecting strip portions of the web produced by cutting into the margins thereof will be bent torsionally to take the form of a screw thread with serrated margins as is generally indicated in Figure 1. Eventually, however, if the torsioning operation is continued the pitch of the imaginary thread represented by the extremities of the laterally projecting strips will become so slight and the strips will become so displaced that the visual effect of the thread will no longer exist and the article will appear as shown in Figure 6, the individual

strips extending in all directions radially from the central core.

The article is now completed for use as tinsel ornaments and by reason of the printing thereon of color bands 30 each of the several strips 60 will carry such bands upon one of its faces whereby to present alternating colored and uncolored light reflecting surfaces in a somewhat symmetrical pattern. The symmetry of the pattern will depend somewhat upon the extent to which twisting or torsion is carried. If the material is not twisted to the extent indicated in Figure 6 and is only twisted sufficiently so that the members 60 are disposed in the path of an imaginary screw thread as is indicated in Figure 7, the completed article will have helical bands of color arranged on symmetrically disposed radially projecting strips. If triangular webs are fed through the machine above described the result will be a tapering tinsel such as that shown in Figure 8 in which the laterally projecting strips are of gradually decreasing length from one end to the other of the completed article. If the core of such a device is reinforced by tensile members 50 and 51 constructed of wire the article will have sufficient rigidity so that the wire core may be thrust into suitable sockets 70 in an artificial tree trunk 71 to simulate the branches 72 of the tree. Very realistic effects are produced thereby particularly if the material of which the tinsel is constructed is green in color. Such material may comprise dyed or painted paper or metallic foil.

In Figure 10 I have illustrated a very important application of this invention to the field of radio signaling. Figure 10 shows a loop aerial having a base 75, a frame 76, and binding posts 77. About the frame 76 is wound a length of such material as that indicated in Figure 6 or, preferably, a length of the material illustrated in Figure 11 and hereinafter to be described. The material is suitably connected at its ends to the individual binding posts 77 and, by reason of its comparatively enormous surface area and the great amount of space which it occupies considering its weight, it is particularly suitable for use as a collector of radio signals.

While ordinary tinsel is sometimes metallic in character it has never so far as I am aware had a continuous metallic path from one end to the other. The fact that in my improved tinsel the laterally projecting strips 60 are integral with the continuously extending unslotted central portion 38 comprising the core makes possible the practical employment of this improved tinsel for aerial purposes.

In Figure 11 the web 25 is illustrated prior to the slitting operation at the lower part of the figure and in the central part of the

figure is shown to have been slotted inwardly from its margins to provide the narrow laterally extending strips 60 already described. Prior to the slitting operation however, the web intended for service as an aerial will preferably be re-enforced centrally by stitching 80 which extends longitudinally and centrally of the web and, upon the completion of the slitting operation, will be disposed centrally of the uncut portion 38 of the web. The material of which the stitches 80 are formed may comprise a very small gage copper or other conductive wire or, due to the fact that portion 38 of the device is continuous and conductive, the stitches may even be taken with non-conductive material such as thread or string. Preferably, however, they will be of wire and will have adequate tensile strength to prevent the aerial from becoming broken by high winds when it is used out of doors. The stitches connect all portions of the aerial electrically as well as mechanically so that even should the foil or other conductive substance employed as web 25 become torn or broken the electrical connection would nevertheless remain complete through the wire used to form the stitches 80.

The device intended for use as an aerial may conveniently be sold in the form in which it appears in the central portion of Figure 11 and may thereupon be twisted by the purchaser. It is obviously more easily handled in its flat form than in its twisted form and it may very readily be twisted as shown in the upper portion of Figure 11 from which the laterally projecting strips 60 have been omitted for purposes of illustration.

It will be obvious that a very small amount of copper or other electrical conductive material by weight may be made in accordance with this invention to present an extremely great amount of surface to the air and may occupy a considerable volume of space when twisted. These characteristics increase its serviceability as a radio aerial far above that of an ordinary wire of equal weight so that a relatively small quantity of the aerial material above described may be used upon a loop frame such as that shown at 76 with comparatively great effectiveness.

Figures 4 and 5 merely show additional forms of knives which may be employed in practicing this invention. In Figure 4 the shear blades 35' and 32' differ from those heretofore disclosed principally in the fact that they are notched at 33' and 46' instead of being provided with the holes previously described. The shear blade in Figure 5 is distinguished by the fact that it will cut or slit one margin only of the web 25 fed therebeneath. It has been found that a web having one margin cut and made of foil or other similar conductive material has an orna-

mental value and a value for aerial purposes second only to that of the articles herein first described.

I claim:

- 5 1. The method of manufacturing tinsel comprising the slitting of the web inwardly from its side margins leaving a continuous central portion of the web unslitted, the application to such portion of re-enforcing tensile members and the twisting of such members whereby to twist said central portion.
- 10 2. As a new article of manufacture a tinsel including a central core, radially projecting strips connected therewith and coloring matter disposed on said strips in a predetermined pattern including a line extending transversely of successive strips and comprising coloring matter disposed on corresponding contiguous portions of successive strips, another part of each such strip being of a different color.
- 15 3. The method of manufacturing tinsel comprising the application to a web of material of a band of coloring pigment having a component of direction longitudinally of said web, the slitting of the web inwardly from the side margins toward its center, whereby to separate from each other narrow strips laterally projecting from a central core and interconnected through said core with each other, said band of color extending across the corresponding portions of a plurality of said strips.
- 20 4. The method of manufacturing tinsel comprising the application to a web of material of a band of coloring pigment having a component of direction longitudinally of said web, the slitting of the web inwardly from the side margins toward its center, whereby to separate from each other narrow strips laterally projecting from a central core and interconnected through said core with each other, said band of color extending
- 25 across the corresponding portions of a plurality of said strips, and subsequently twisting said core to leave said strips projecting therefrom at a variety of radial angles whereby said band of color will follow a helical path across consecutive strips.
- 30 5. As a new article of manufacture a tinsel comprising integrally a continuous central portion, strips projecting laterally therefrom and opposed tensile members reinforcing said central portion upon opposite sides thereof and twisted to support said strips at a variety of radial angles.
- 35 6. The method of producing a tinsel having a predetermined pattern in color applied to the variously directed strips thereof, such method including a deposit of pigment in predetermined pattern upon a web of suitable material, the slitting of said web to provide strips suitable for tinsel and the subsequent twisting of said strips between opposing tensile members to project them at a variety of angles, whereby predetermined portions of the variously angled strips in the completed product may be colored in accordance with a predetermined plan.
- 40 7. The method of manufacturing tinsel comprising the slitting of a web of material inwardly from its side margins leaving a continuous central portion of the web unslitted, placing a pair of wires one upon each side of said unslitted portion of the web, and twisting together the unslitted portion of the web and wire, whereby to project radially about the twisted portion of said tinsel the slitted margins of said web.
- 45 8. As a new article of manufacture a tinsel comprising a web of material having strips projecting laterally of the web, and a pair of wires one upon each side of said web, said web and wires being twisted together, whereby the strips project radially about said twisted web and wires.

WILLIAM H. SCHNEIDER.
